HINGES AND CONSTRUCTIONS INCORPORATING THE SAME

Raymond D. La Pan, Graniteville, Mass., assignor to C. G. Sargent's Sons Corp., Graniteville, Mass., a corporation of Massachusetts

Filed Sept. 30, 1965, Ser. No. 491,754
7 Claims. (Cl. 16—147)

ABSTRACT OF THE DISCLOSURE

Hinge for attaching a panel to a wall and having a first portion engageable with the front of a pintle and a second portion at the end of a spring-pressed pin engageable with the back of the pintle, the two portions so encircling the pintle as to provide a pivotal connection releasable by retracting the pin with the second portion being forced from its operative position when the panel is swung shut or when a predetermined pressure is exerted on its back surface, with means to adjust the position of the second portion relative to the pintle, and with means for adjusting the position of the spring.

The present invention relates to hinges and to constructions incorporating the same.

While hinges in accordance with the invention may be used in various constructions, the objective of the invention may be most readily understood by considering such material treating apparatus as driers of the type having treating chambers of substantial length through which a conveyor extends. It is desirable to have the sides of such chambers provided with removable panels along both sides to provide ease and convenience in meeting servicing requirements.

The general objective of the invention is to provide hinges that may be used to attach panels to a drier side wall, the hinges being releasable so that when all are disconnected, the panel may be removed while, if only those along either side are released to function as latches, the hinges along the other side can then function to enable that panel to be swung open or shut.

In accordance with the invention, this objective is attained by providing a hinge having a pintle attachable to an upright and a plate attachable to a panel and including an outwardly disposed end flange provided with a portion overlying and engaging the pintle, a pin provided with a pintle-engaging portion extending in back of the pintle and slidably held by a guide on the plate for movement in a path at right angles to the axis of the pintle into a position in which its pintle-engaging portion is retracted from its pintle-engaging position. A spring yieldably urges the pin into its pintle-engaging position and the pintle-engaging portions of the flange and the pin so encircle the pintle as to provide a pivotal connection between the plates that is released by the retraction of the pin. Such a hinge may include two axially aligned pintles in which case there may be two identical plates, one inverted relative to the other, and each for attachment to a respective one of two adjacent panels.

To ensure that the hinges, when installed, are adjustable to function, in a desired manner, to permit a panel to be swung shut, for example, without manually retracting the hinge pin or pins at one side of a panel, it is necessary that the pintle-engaging portion of each hinge that is to function as a latch be so positioned as to engage its pintle short of a lengthwise plane inclusive of the pintle axis and at right angles to the upright supporting that pintle so that it can be momentarily cammed by engagement therewith against the action of the spring of the hinge to enable it to enter in back of its pintle when the flange portion

2

is in engagement therewith. Adjustable stop means are, accordingly, incorporated into hinges in accordance with the invention to enable the pintle-engaging portion of each hinge to be accurately adjusted and adjustable means are also provided to vary the action of each spring.

In some drier uses, it is desirable to have the panels open if there is an explosion in the treating chamber and this may be effected by so adjusting the springs of the hinges at one side of a panel to yield more readily than those at the other side thereof.

In the accompanying drawings, there is shown an illustrative embodiment of the invention from which these and other of its objectives, novel features, and advantages will be readily apparent.

10 In the drawings:

FIGURE 1 is a fragmentary side view of a drier showing a panel connected thereto by hinges in accordance with the invention,

20 FIGURE 2 is a fragmentary section taken approximately along the indicated lines 2—2 of FIGURE 3,

FIGURE 3 is a fragmentary and partly sectioned face view, on an enlarged scale, of one of the hinges,

25 FIGURE 4 is a section taken approximately along the indicated lines 4—4 of FIGURE 3, and

FIGURE 5 is a fragmentary view, on a further increase in scale, of the pintle and the pintle-engaging portion of one of the pins.

In the embodiment of the invention illustrated by the drawings, panels 5, 5A, and 5B are shown as having their proximate sides connected to the uprights 6 of a drier chamber 7 by generally indicated hinges 8.

30 Each hinge 8 includes a pintle 9 attached to a plate 10 by end supports 11 and by an intermediate support 12 spaced equally from the end supports and dividing the 35 pintle 9 into upper and lower portions of equal length. Each plate is attached to an upright 6.

Each hinge 8 also includes a single plate 13 in the case of an end panel and a pair of plates 13 when it is to be used in the support of adjacent panels. Each plate 13 is 40 shown as including upper and lower portions defined by the center lines along which are disposed the screws 14 by which it is attached to a panel. Each plate has an outwardly disposed end flange 15, at one side of its center line, terminating in an inwardly opening, arcuate channel 45 16 dimensioned to fit, when the panel to which it is attached is in place, between the intermediate support 12 and one of the end supports 11 and against the portion of the pintle 9 exposed therebetween.

45 Each plate 13 has, on the same side of its center line as the flange 15, a housing 17 within which there is a guide 18 provided with a bushing 19 slidably supporting a pin 20 in transverse alignment with a passageway 21 in the flange 15 and engageable with the pintle 9 and having an end portion 20A and an intermediate portion 50 20B threaded to receive a nut 22 and a nut 23.

55 The threaded portion 20B extends through a coiled compression spring 24 resiliently bearing against the nut 21, by which its tension may be adjusted, and against the guide bracket 25 which is shown as secured to a boss 26 as by screws 27. The pin 20 is thus yieldably urged into engagement with the pintle 9 when the panel is in place, otherwise outwardly beyond the flange 15 until the nut 23 engages the proximate end of the bushing 19, the nut 23 thus serving as an adjustable stop. The pin end portion 20A extends freely through the bracket 25. A handle 28 is held by a screw 29 serving as a pivot and threaded into the boss 26. The handle 28 has a depending arm 30 having a slot 31 slidably confining a pin 32 on the free end of the pin end portion 20A. With the hinge shown in the drawings, the handles 28 are yieldably held in a vertical position by the spring 24 but may

be swung manually towards a horizontal position to retract the pin 20 from its operative, pintle-engaging position.

Referring now to the pintle-engaging end of the pin 20 when it is to function as a latch, it will be noted that it has a vertical recess, arcuate with respect to the pintle 9 providing shoulders 33 and 34. It will also be noted that the shoulder 33 is shorter than the shoulder 34 and terminates short of a vertical plane axially of the pintle 9 and at right angles to the upright 6 when the panel is in its closed position.

With a panel mounted at both sides to uprights 6 by the hinges 8, the hinges or hinge at either side may be released to function as latches with the hinges 8 at the other side then being operative to permit the panel to be swung open. By releasing the hinges 8 at both sides, a panel may be removed and replaced and as the center lines of corresponding hinges are transversely aligned and uniformly spaced from the ends of the panels, the panels may be interchanged and mounted on the uprights, either end up.

It will also be appreciated that the disposition of the shoulders 33 relative to the pintles 9 enables the pintles 9 to cam the pins 20 out of their operative positions as when a panel is swung shut, or, when shut, if the pressure builds up in back of a panel to a predetermined extent as is desired, in some drier uses, in case of an explosion therein. It will also be appreciated that adjustments of each nut 23 enable the operative position of the shoulder 33 to be precisely set while adjustments of each nut 22 enable the resistance of each spring 24 to movement of the associated pin 20 to be controlled to ensure the desired operation.

It will be noted that in order for two panels to be connected to the same upright and to be reversible, the pintle-engaging pins 20 of the two plates 13 must be located one higher than the other. With the plates shown in the drawings, one is inverted relative to the other when turned end-for-end in order to permit this arrangement but because of the size and shape of the plates 13, a balanced appearance is achieved.

I claim:

1. A hinge including a pintle, a plate including an outwardly disposed end flange provided with a portion overlying and engaging said pintle, a pin including a pintle-engaging portion extending back of said pintle, means slidably connecting said pin to said plate for movement in a path at right angles to the axis of said pintle into a position in which said pin portion is retracted from its pintle-engaging position, and a spring carried by said plate and connected to said pin and yieldably maintaining said pintle-engaging portion in engagement with said pintle, said flange and pintle-engaging portions so encircling said pintle as to effect the pivotal interconnection of said plates disconnectable when said pin is retracted but with the pintle-engaging portion terminating short of a vertical plane through the axis of the pintle at right angles to the pin axis when in engagement with the pintle.

2. The hinge of claim 1 and means to adjust the position of the pintle-engaging portion of the pin relative to the pintle.

3. A hinge including a pintle, a plate including an outwardly disposed end flange provided with a portion overlying and engaging said pintle, a pin including a pintle-engaging portion extending in back of said pintle and terminating short of a plane lengthwise of the axis of the pintle and at right angles to the pintle, a guide on said plate slidably supporting said pin for movement in a path at right angles to the axis of said pintle into a position in which said pintle-engaging portion is retracted from its pintle-engaging position, said pin including end and intermediate portions, a bracket through which said pin end portion extends, said intermediate pin portion being threaded, first and second nuts threaded on said intermediate pin portion, a spring interposed between and

resilient bearing against bracket and said first nut and yieldably maintaining said pintle-engaging portion in engagement with said pintle with its effect adjustable by turning said first nut in one direction or the other, said flange and pintle-engaging portions so encircling said pintle as to effect a pivotal interconnection disconnectable when said pin is retracted, and said second nut being engageable with said guide to limit the position of said pin portion when said hinge is disconnected and being adjustable by turning said second nut in one direction or the other.

4. The hinge of claim 3 in which the end flange has an opening through which the pin extends.

5. A hinge including a pintle, a plate including an outwardly disposed end flange provided with a portion overlying and engaging said pintle, a pin including a pintle-engaging portion extending in back of said pintle and terminating short of a plane lengthwise of the axis of the pintle and at right angles to the pintle, a guide on said plate slidably supporting said pin for movement in a path at right angles to the axis of said pintle into a position in which said pintle-engaging portion is retracted from its pintle-engaging position, said pin including end and intermediate portions, a bracket through which said pin end portion extends, said intermediate pin portion being threaded, first and second nuts threaded on said intermediate pin portion, a spring interposed between and resiliently bearing against said bracket and said first nuts and yieldably maintaining said pintle-engaging portion in engagement with said pintle with its effect adjustable by turning said first nut in one direction or the other, said flange and pintle-engaging portions so encircling said pintle as to effect a pivotal interconnection of said hinge disconnectable when said pin is retracted, and said second nut being engageable with said guide to limit the position of said pin portion when said hinge is disconnected and being adjustable by turning said second nut in one direction or the other, a handle pivotably connected to said second plate, and a connection between said handle and the extremity of said pin end portion operable to move said pin towards its retractable position as said handle is swung in a predetermined direction.

6. A hinge including a pair of aligned pintles, a pair of identical plates disposed at right angles to the axis of said pintles but in opposite directions, each including an outwardly disposed end flange provided with a portion overlying and engaging one of said pintles, a pin including a pintle-engaging portion extending in back of said one pintle portion and terminating short of a plane lengthwise of the axis of the pintles and at right angles to said pintle, a bracket and a guide, the guide slidably supporting the pin of that plate for movement in a path at right angles to the axis of said pintles into a position in which said pintle-engaging portion is retracted from its pintle-engaging position, said pin including end and intermediate portions, the pin end extending through the guide, first and second nuts threaded on said intermediate portion, a compression spring interposed between and resiliently bearing against said bracket and said first nut and yieldably maintaining said pintle-engaging portion in engagement with the appropriate pintle portion with its effect adjustable by turning said first nut in one direction or the other, each flange and associated pintle-engaging portion so encircling the pintle as to effect a releasable pivotal interconnection therewith, and said second nut being engageable with said guide as an adjustable stop.

7. In combination, a wall including a series of frames interconnected side-by-side, a panel for each frame, hinges connecting both sides of each panel to both sides of a frame, each hinge including a pintle, a plate including an outwardly disposed end flange provided with a portion overlying and engaging said pintle, a pin including a pintle-engaging portion extending in back of said pintle, means slidably connecting said pin to said second plate for movement in a path at right angles to

the axis of said pintle into a position in which said pin portion is retracted from its pintle-engaging position, a spring carried by said plate and connected to said pin and yieldably maintaining said pintle-engaging portion in engagement with said pintle, means to adjust the opposition of said spring to retraction of said pin, and an adjustable stop limiting movement of said pin by said spring, said flange and said pintle-engaging portions so encircling said pintle as to effect a pivotal interconnection that may be disconnected by retracting said pin whereby the hinges for a panel may be disconnected to enable that panel to be removed or the hinges at their side may be disconnected to enable the panel to be swung on the hinges at the other side, said pintle-engaging portion terminating short of a vertical plane

through the axis of the pintle at right angles to the pin axis when in engagement with the pintle thereby to function as a cam to force said pin against the resistance of said spring as the panel is swung shut and when a predetermined pressure is exerted against the interior surface of the panel.
